UNITED STATES PATENT OFFICE.

HENRY CHARLES HARRISON, OF BIRMINGHAM, ENGLAND.

TOY BUILDING ELEMENTS.

1,095,858.

Specification of Letters Patent.

Patented May 5, 1914.

Application filed June 21, 1913. Serial No. 775,121.

To all whom it may concern:

Be it known that I, HENRY CHARLES HARRISON, subject of the King of Great Britain, residing at "Stoneleigh," Mayfield Road, 5 Mcseley, Birmingham, England, have invented certain new and useful Improvements in Toy Building Elements, of which the following is a specification.

This invention relates to elements employed for building toy structures, such as toy bridges, cranes, and other objects, the said elements being of that type consisting of lengths of tubing provided at one or both ends with a clip or clips whereby they may 10 be detachably or interchangeably connected together. Previously such elements have been of a square section and have been provided with clips having parallel straight jaws but according to the present invention 15 they are formed of a circular cross-section and provided at one or both ends with a pair of substantially semi-circular or bow-shaped spring jaws, whose extremities are bent outward into leads whereby they may be readily engaged or sprung over the shank or 20 body part of another element. The circular cross-section of the elements permits of their being connected together in any position in a plane at right angles to one another. 25

Figure 1 of the accompanying drawings shows, by way of example, a model of a crane formed by building elements constructed in accordance with this invention. 30 Fig. 2 shows on a larger scale a number of the building elements illustrating more clearly the manner in which they are connected together. Fig. 3 is a further view of a number of elements connected together. 35 Fig. 4 shows several views of a single element. Fig. 5 illustrates elevational and cross-sectional views of an element which is formed with an attachment clip at one end only.

40 The same reference numerals indicate corresponding parts in each of the figures.

Referring to Figs. 1 to 4 each of the building elements 1 is formed from a single sheet metal blank which is bent up into the form 45 of a circular sectioned tube, the said tube having an open joint 2 formed by the opposed edges of the blank and extending longitudinally down one side, as shown in Fig. 4. The tube is also split at each end at 50 55 3 for a portion of its length so that a slight resiliency is imparted to its walls. It is

further formed at the said ends with a pair of integral spring jaws or clips 4, which are opposed to each other and bowed outwardly and adapted to be sprung over the shank or 60 body part of an adjacent or other tube member or building element, so as to firmly grip same, so that the two tubes or elements are securely but detachably connected together.

The extremities of the spring jaws or clips 65 4 are bent outward and formed into lips 5 so as to constitute a lead for enabling said clips to be readily and easily engaged with the element to which they are to be connected the engagement of the jaws being 70 further facilitated owing to the walls of the element with which they are engaged giving slightly to the pressure. Some of the elements 1 may be formed with a clip or pair of jaws 4 at one end only as shown in Fig. 5 75 of the drawings. The said tubes or elements are preferably formed of a circular cross-section, as above described, so as to admit of any two elements being connected together in any position in a plane at right angles to one another. Terminal ornaments may be secured to any of the elements of the structure by means of clips in a similar manner.

Having fully described my invention, 85 what I desire to claim and secure by Letters Patent is:—

1. A toy building element consisting of a hollow, cylindrical tube having a terminal clip which is formed integral therewith and 90 comprises a pair of opposed substantially bow-shaped spring jaws whose extremities are bent outward to form leads.

2. A toy building element consisting of a hollow, cylindrical tube which is split longitudinally and provided with a terminal clip, 95 said clip being formed integral with said tube and comprising a pair of opposed substantially bow-shaped spring jaws whose extremities are bent outward to form leads.

3. A toy building element formed from a single sheet metal blank which is bent up into a hollow, cylindrical tube being provided with an open joint, the said tube having a terminal clip which is formed integral therewith and comprises a pair of opposed substantially bow-shaped jaws whose extremities are bent outward to form leads.

4. A toy building element consisting of a hollow, cylindrical tube which has a longitudinal gap extending its whole length, and which is also split at the end for a portion

of its length at a point diametrically opposite to the said gap, said tube being provided with a terminal clip comprising a pair of opposed substantially bow-shaped jaws 5 whose extremities are bent outward to form leads.

5. A toy building element consisting of a hollow, cylindrical split tube, having, at each end, a pair of opposed substantially 10 bow shaped spring jaws whose extremities

are bent outward to form leads, said jaws being formed integral with said tube.

In testimony whereof I have hereunto set my hand in presence of two subscribing witnesses.

HENRY CHARLES HARRISON.
